UNITED STATES PATENT OFFICE

ELMER ELLSWORTH WILT, OF CHICAGO, ILLINOIS

DESIGN FOR A TRAY FOR SUITCASES

Application filed February 17, 1930. Serial No. 34,571. Term of patent 14 years.

To all whom it may concern:

Be it known that I, ELMER ELLSWORTH WILT, a citizen of the United States, residing at Chicago, in the county of Cook and State of Illinois, have invented a new, original, and ornamental Design for a Tray for Suitcases, of which the following is a specification, reference being had to the accompanying drawing, forming part thereof.

The drawing shows a perspective view of a tray for suit cases showing my new design.

I claim:—

The ornamental design for a tray for suit cases, as shown.

ELMER ELLSWORTH WILT.
